CLAIM

The ornamental design for a transforaminal lumbar interbody fusion device, as shown and described.

DESCRIPTION

FIG. 1 is a first top perspective view of a transforaminal lumbar interbody fusion device in accordance with an embodiment of the present invention, wherein a corresponding bottom perspective view is an identical mirror image; FIG. 2 is second top perspective view of the transforaminal lumbar interbody fusion device shown in FIG. 1, wherein a corresponding bottom perspective view is an identical mirror image;

FIG. 3 is third perspective view of the transforaminal lumbar interbody fusion device shown in FIG. 1, wherein a corresponding bottom perspective view is an identical mirror image;

FIG. 4 is front tip elevation view of the transforaminal lumbar interbody fusion device shown in FIG. 1;

FIG. 5 is front elevation view of the transforaminal lumbar interbody fusion device shown in FIG. 1;

FIG. 6 is rear elevation view of the transforaminal lumbar interbody fusion device shown in FIG. 1;

FIG. 7 is a top view of the transforaminal lumbar interbody fusion device shown in FIG. 1;

FIG. 8 is a bottom view of the transforaminal lumbar interbody fusion device shown in FIG. 1;

FIG. 9 is a left side elevation view of the transforaminal lumbar interbody fusion device shown in FIG. 1; and,

FIG. 10 is a right side elevation view of the transforaminal lumbar interbody fusion device shown in FIG. 1.
